THERMIONIC DISCHARGE DEVICE

John F. Peters, Pittsburgh, Pa., assignor to Westinghouse Electric & Manufacturing Company, a corporation of Pennsylvania

Application August 30, 1923, Serial No. 660,093

4 Claims. (Cl. 250—27.5)

My invention relates to thermionic discharge devices.

Broadly speaking, the object of my invention is to provide a cathode for a thermionic discharge device which avoids the difficulties encountered in heating thermionic cathodes by alternating current.

More specifically, the object of my invention is to provide a heated cathode construction for a thermionic discharge device in which means are provided whereby the cathode can be heated by alternating current and means whereby the modulating effect of the alternating magnetic field produced by alternating current as encountered in the usual single filament cathode structure of the prior art is nullified.

In thermionic discharge devices constructed according to the prior art, a single filament is customarily used. This filament is usually heated by a flow of low voltage direct current. Many such devices have been constructed with a filament cathode of such size as to be heated to the operating temperature by a current of approximately one ampere, supplied at a voltage of approximately 6 volts. This current is customarily supplied from a storage battery. However, it would be much more convenient to supply the heating energy as alternating current from commercial frequency circuits by a transformer at a suitable voltage.

When this has been attempted in the past, however, difficulties have been experienced due to the fact that the magnetic field incident to any heating current produces an influence upon the electron stream. When direct current is used for a heat energy supply the magnetic effect is constant, and steady in value, and therefore, produces no pulsating modulation effect on the electron stream to be recognized as a sound in the receiving apparatus employed in conjunction with the tube. When, however, alternating current is used with a single filament cathode, the pulsations of the current produce a varying magnetic effect upon the electron stream which causes a magnetic modulation and is perceived as a sound in a telephone device employed in conjunction with the system containing such filament cathode.

My invention provides a cathode construction consisting of two filaments placed in juxtaposition, and connected to the same energy source in such way that they carry substantially equal currents in opposite directions. These opposite currents produce opposing magnetic fields. These fields, by virtue of their opposition, neutralize each other and thereby avoid the mag-

netic modulation effect which occurs with the single filament when heated by alternating current.

Other objects and structural details of my invention will be apparent from the following description and claims when read in connection with the accompanying drawings, wherein:

Figure 1 is a view in elevation of a cathode constructed according to my invention.

Fig. 2 is a view in elevation of a vacuum tube having a cathode constructed according to my invention in operative relation to a flat grid and plate of the pattern employed in a typical triode, and

Fig. 3 is a view similar to Fig. 2 illustrating the cathode in conjunction with a cylindrical grid and cylindrical plate.

In the figures, similar structures have the same reference numbers.

In the structure of Fig. 1, a press 1 carries sealed-in conductor and supporting wires 2, 3, 4, 5 and 6. Two adjacent filaments 7 and 8 are attached at their ends to conductor wires 3 and 5 and are supported at their centers by supporting wire 2. Wires 11 and 12 serve as connectors for conducting the current from the lead wires 3 and 5 to the ends of filaments 7 and 8.

In the arrangement shown in Fig. 2, a press 1 is provided, as before. Lead and supporting wires 2, 3, 4, 5, 6, 13 and 14 are also provided as are filaments 7 and 8. In addition, a grid 15 supported on wires 6 and 14 and a plate 16 supported on wires 4 and 13 are provided. A container 17 of glass or other suitable material is provided.

The structure of Fig. 3 is similar to that of Fig. 2 except that a cylindrical grid 21 and a cylindrical plate 22 are provided instead of the flat grid and plate.

In the operation of my device, an alternating current source is connected to leads 3 and 5. Current flows between the leads by way of filaments 7 and 8 in such manner that the respective portions of the filaments of opposite polarity and in juxtaposition to each other carry currents in opposite directions. Potential is also impressed between the filament structure and an adjacent anode structure, whereupon an electron stream carries the current between the anode and the cathode. Modulation of this electron stream by a magnetic field produced by the alternating current in the filament cathode structure is, however, avoided by reason of the neutralization of the field of one filament by the field of the adjacent filament.

While I have illustrated but one embodiment

of my invention, it will be apparent to those skilled in the art that various changes and modifications may be made without departing from the spirit and scope of my invention and it is desired, therefore that only such limitations shall be imposed thereon as are indicated in the prior art or as set forth in the appended claims.

I claim as my invention:

1. An electron-discharge device comprising a cathode structure having more than two current-carrying members comprising two groups to carry current in opposite directions, individual members of one group being more closely adjacent to a member of the other group than to any member of their own group.

2. An electron-discharge device comprising a cathode structure having a pair of current-carrying loops, the sides of each loop being more distant from that side of the other loop which carries current of the same direction than from that

side of the other loop which carries current of the opposite direction.

3. An electron-discharge-tube device comprising a cathode having two substantially hair-pin-shaped filaments, said filaments crossing each other at their bights, a common support for said bights, the sides of each filament being relatively far apart from each other, each filament-side being farther from that side of the other filament which carries current in the same direction than from that side of the other filament that carries current in the opposite direction as itself. 5

4. A thermionic tube having plate and grid elements therein, an even number of filaments, and connections for conveying a heating current to said filaments, each of said filaments having a part lying substantially alongside a neighboring filament, and connected to cause the instantaneous direction of flow in such parts of the two filaments to be substantially opposite. 10 15 20
